Fig. 1

Fig. 2

Fig. 3

Fig. 4

FIG. 1 is a side elevational view of a display stand embodying the invention.

FIG. 2 is a bottom view of the display stand shown in FIG. 1.

FIG. 3 is a top view of the display stand shown in FIG. 1.

FIG. 4 is a side elevational view of the display stand shown in FIG. 1 but rotated to an alternate position.

The faces of the stand not shown in FIGS. 1 and 4 are the same in appearance as the faces shown. The leg members appear wider in FIG. 4 than in FIG. 1 due to the difference in the angular orientation of the two figures.

I claim:

The ornamental design for a display stand or similar article, as shown and described.
